IGNAZ ZEISSL, OF VIENNA, AUSTRIA, ASSIGNOR TO STERN-GESELLSCHAFT FUR MODERNE GRUNDBAUTECHNIK M. B. H., OF VIENNA, AUSTRIA, A COMPANY OF AUSTRIA

PILE

Application filed June 22, 1928, Serial No. 287,595, and in Austria November 21, 1927.

This invention relates to improvements in the arrangement for starting the drawing motion of piles or of a pile core in the case of sinking metal tubes.

According to the present invention the removable point of the pile is pressed into the ground in a known manner without lifting the pile.

The operation of the mechanical means, which are located above the ground and serve for lifting the pile away from the shoe and usually consist of winches with long handles, is very troublesome and a manual operation is rendered possible only, because the arrangement of large machines is connected with difficulties. Also the application of metal sleeves and the necessary accessories is troublesome and expensive. Thin-walled metal sleeves have to be short, they draw up on the core and are raised when lifting the latter. Thin-walled metal sleeves of some length cannot be employed in view of the danger of breaking off. Thick-walled metal sleeves of some considerable length, cannot be used with advantage in view of their high costs.

These drawbacks are avoided by the arrangement according to the present invention.

The essential feature of the present invention consists in that an hydraulic press is disposed between the pile-shoe and the pile, whereby the latter is raised when introducing a pressure medium.

Preferably the pile-shoe is shaped in such a manner, that it forms a part of an hydraulic press, which cooperates with the corresponding other part of the press formed by the pile. Besides simple handling, this construction possesses the further advantage, that great forces, different ratios and great effects are rendered possible.

A further feature of the arrangement according to the present invention consists in that one or more bands of iron, steel or the like are passed round the pile-shoe and are fixed to the point of the latter and further pass up along the pile to the top of the latter, in order to prevent the pile-shoe from penetrating further into the ground or soil

when lifting the pile or pile-core and thus provide for a positive lift of the pile.

One mode of carrying out the present invention is illustrated by way of example on the accompanying sheet of drawings in which:—

Figs. 1 and 2 show the pile in sectional elevation and plan view respectively.

The end of the pile or pile-core 1 is provided with a press-cylinder 2, which is in communication with a pressure liquid pump by means of a pipe 3, passing through the pile. The pile-shoe 4 constitutes the piston of the press. The pile 1 is forced away from the shoe 4 when pumping the pressure liquid into the pipe 3.

The middle portion of bands 5 (in the present case two bands of steel, iron or the like) is secured between the piston-like pile-shoe 4 and the point 6 of the pile in such a manner, that the bands pass upward along the pile 1, the said bands being not attached to the latter, but solely are guided in a clip 7, which passes round the pile.

Of course the attachment of bands to the pile-shoe is not limited to the employment of an hydraulic arrangement, because the same advantages can be attained when using the bands in connection with a spindle or the like.

The arrangement operates in the following manner:—

Three different forces act on the pile-core, namely its own weight as pressure from above, the friction of the bands when drawing as a pulling force from the bottom, and the press-cylinder as pressure from the bottom. Therefore the pressure of the press-cylinder exceeds, even if slightly only, the pulling action of the bands and its own weight, the entire system will be relaxed shortly and the bands can slacken, so that the core and bands together with the point can be readily withdrawn. Thereby the following forces act on the point and bands, namely the pressure of the press-ram acts downward, the pull of the friction of the bands acts upward and the resistance of the bottom of the pit acts upward. The downward pressure of the press-ram is greater

than the frictional upward pull of the bands for the weight of the pile-core only, and therefore a small force only will have the tendency to force the point into the ground 5 and the same will be readily taken up by the floor of the pit without compression.

If a metal sleeve or a number of metal sleeves is or are used as pit-tubing in order to prevent the collapse of the pit, the former can be pushed onto the pile-core without having to be connected with each other or with the pile-shoe. Thus the sleeve may 10 be in the form of a smooth sheet metal tube

8. When driving the pile (pile-core), the 15 preferably conical and loose tubes 8 (if they consist of several parts they are telescopically fitted into one another) are tightly pulled onto the pile (pile-core) owing to the force due to the masses and the friction 20 of the earth and are driven into the soil. The action of the bands is again operative during the withdrawal. The pile-core is forced upward, whereby the bands and with them the sheet metal sleeves are held down.

25 Owing to the conical shape of the core, the pressure between the pile-core, bands and metal sleeves is interrupted after the lift of the core, and the latter together with the bands can be pulled out without difficulty, 30 while, in consequence of their own tension, the metal sleeves remain in the ground as lining of the pit and are immovably secured in their original position until the entire relaxation of the supporting bands.

35 I claim:—

1. A device for forming pit holes for piles comprising in combination a pile core, a pile shoe, and an hydraulic press located between the pile core and pile shoe said parts 40 forming a removable unit.

2. A device for forming pit holes for piles comprising in combination a pile core formed as a part of an hydraulic press, and a pile shoe formed as the corresponding 45 other part of the said press and cooperating with the pile core.

3. A device for forming pit holes for piles comprising a pile core, a pile shoe, and a metal band secured only to the point of the 50 pile shoe and passing upward along the pile core.

4. A device for forming pit holes for piles comprising a pile core, a pile shoe, and a number of metal bands secured only to the 55 point of the pile shoe and passing upward along the pile core.

5. A device for forming pit holes for piles comprising a pile core, a pile shoe, and a metal band, the middle portion of the latter being clamped between the pile shoe and the point of the same, while the free ends of the said band pass upward along two sides of the pile core.

6. A device for forming pit holes for 65 piles comprising a pile core, a pile shoe, a

metal band secured only to the point of the pile shoe and passing upward along the pile core, and means on the pile core for guiding the free end of the band.

7. A device for forming pit holes for 70 piles comprising a pile core, a pile shoe, a metal band, the middle portion of the latter being clamped between the pile shoe and the point of the same, while the free ends of the said band pass upward along two sides 75 of the pile core, and means on the pile core for guiding the free ends of the said band.

In testimony whereof I affix my signature.
